UNITED STATES PATENT OFFICE.

MILLARD E. BRINSER, OF YORK, PENNSYLVANIA.

LIQUID RECEPTACLE AND EJECTING DEVICE.

1,277,842.

Specification of Letters Patent.

Patented Sept. 3, 1918.

Application filed May 15, 1917. Serial No. 168,655.

To all whom it may concern:

Be it known that I, MILLARD E. BRINSER, a citizen of the United States, and a resident of York, in the county of York and State of Pennsylvania, have invented a new and useful Improvement in Liquid Receptacles and Ejecting Devices, of which the following is a specification.

My invention relates to improvements in liquid receptacles and ejecting devices and it consists in the combinations, constructions and arrangements herein described and claimed.

An object of my invention is to provide a liquid receptacle having means for either automatically or manually ejecting the liquid.

A further object of my invention is to provide a receptacle which may be entirely filled with liquid but which is provided with a spring designed to move a piston in such a manner that one-half of the liquid may be ejected and the other half may be ejected subsequently upon the retraction of the spring by manual means.

A further object of my invention is to provide a device of the type described in which the automatic ejection may be controlled at any point in this movement manually.

Other objects and advantages will appear in the following specification and the novel features of the invention will be particularly pointed out in the appended claims.

My invention is illustrated in the accompanying drawings, forming part of this application, in which

Figure 1 is a side view of one embodiment of my invention, certain parts being shown in section,

Fig. 2 is an enlarged section through the piston or plunger and parts of the receptacle,

Fig. 3 is a section on the line 3-3 of Fig. 2,

Fig. 4 is a longitudinal central section through the device,

Fig. 5 is a perspective view of an inner sleeve,

Fig. 6 is a section on the line 6-6 of Fig. 4,

Fig. 7 is a section on the line 7-7 of Fig. 4,

Fig. 8 is a perspective view of a portion of the upper part of the sleeve shown in Fig. 6,

Fig. 9 is an enlarged section along the line 9-9 of Fig. 4.

My invention may be applied to various uses such as that of a fire extinguisher, or means for ejecting disinfectants or insecticides, etc. In Fig. 1 I have shown a receptacle which may be used for a number of different purposes. This receptacle consists of a cylindrical casing 1 which is provided at its top with a hemispherical cap 2 and at the bottom with a screw cap 3. Disposed within the casing 1 is a plunger 4 which has openings 5 therethrough. This plunger has a central hub portion 6 which is threaded on the end of a sleeve 7. The hub portion 6 is hollow. It contains a screw head 8 which is normally pressed upon by a spring 9. The opposite end of the screw is threaded into the stem of a valve 10 which slides in an auxiliary portion of the piston 4.

The sleeve 7 is provided with guide lugs 7^a which enter slots 8^a in an exterior cylinder 8, see Fig. 7, which is threaded at its upper end into the cover portion 2. This permits the sleeve 7 to move longitudinally with respect to the cylinder 8. The upper end of the sleeve 7 is enlarged and is provided on its interior with threads 11. This constitutes a nut for a screw shaft 12. The latter has a collar 13 and is provided with a bearing 14 in a recess in the cap 2. At the end of the screw shaft is a nut 15 which serves the double function of clamping the hand wheel 16 and also drawing up the shaft so that the collar 13 will be frictionally engaged and thus lock the shaft thereby preventing rotation.

Disposed within the casing 1 is a spiral spring 17 which bears at one end on the piston 4 and at the other end on a shoulder formed by the cap or cover 2. At the lower end of the device is a valve 18 whose stem is threaded into a plunger 19 which is movable in guides 20. A spring 21 normally presses on the plunger 19 so as to keep the valve 18 closed. A nozzle 22 is provided which is screwed into the threaded extension 23.

From the foregoing description of the various parts of the device the operation thereof may be readily understood.

The device is filled through the opening normally closed by the screw plug 24. The latter has an air opening 25 for permitting air to enter as the liquid is ejected. Let us

assume that the device is filled with liquid both in the upper and lower portions and that the spring has been compressed to the extent shown in Fig. 4. In this figure the 5 collar 13 is shown in close engagement with its seat, this seat being the end of the exterior cylinder 8. The screw shaft 12 is therefore prevented from turning. The spring 17 is, however, under compression.

- 10 Now if it is desired to eject the liquid suddenly as, for instance, where the device is used as a fire extinguisher, all that is necessary is to loosen the nut 15, whereupon the spring will force the piston 4 downwardly. The engagement of the screw head 8 with the end of the screw shaft 12 keeps the valve 10 open but when the piston moves downwardly the spring 9 tends to cause the closing of the valve as shown in 15 Fig. 2, since the head has moved away from the screw shaft 12. The sleeve 7 is pushed downwardly by the movement of the piston 10 but does not rotate because it is feathered to the exterior cylinder 8 as already explained. The movement of the sleeve, however, causes the rotation of the shaft 12 and of the hand-wheel 16 which is carried by it. This is facilitated by the provision of the bearings 14. The liquid from the lower 20 part of the chamber forces open the check valve 18 and passes through the nozzle 22. The valve 10 closes the openings 5 and prevents the liquid in the upper part of the receptacle from escaping. The valve 18 will 25 not open by the weight of the liquid alone, but it will open when the pressure of the spring 7 is brought into play or when manual force is used as hereinafter described.
- 30 40 The movement of the piston 4 downwardly may be stopped at any point by catching hold of the hand wheel 16 and then tightening up on the nut 15. Thus when a fire has been extinguished the stopping of 45 the automatic ejecting means will of course save some of the extinguishing fluid.

When the piston has reached the bottom and the liquid in the lower part has been ejected the piston may be returned to its 50 original position and the spring 17 compressed by manipulation of the hand wheel 16. The shaft 12 then acts to pull on the threaded portion 11 of the sleeve 7 to which the piston is attached. The valve 10 re- 55 mains closed until the screw head 8 engages the end of the screw shaft 12 when the valve will open and let the liquid in the upper portion of the receptacle flow through the openings 5 into the lower portion. The liquid in 60 the lower portion may now be expelled in precisely the same manner as that already described.

When the nut 15 is loosened it will of course be possible to assist the spring 17 by 65 turning the hand wheel in the direction in

which it is being turned by the spring or to stop the movement by exerting pressure on the wheel in the opposite direction as described. Obviously the device could be operated by removing the spring 17 entirely 70 since the turning of the hand wheel 16 would cause the piston to move downwardly or upwardly according to the desire of the operator.

It will be seen that I have provided a device in which an automatic movement is effected when the nut 15 is once loosened and that this automatic movement results in the ejection of one-half of the liquid, the other 80 half being capable of being ejected by either a subsequent automatic movement or by a manual movement.

I claim:

1. A liquid-receptacle and ejecting device comprising a casing having a nozzle, said 85 casing being arranged to receive a liquid, a piston within the casing, a spring for placing said piston normally under tension, a valve adapted to open under pressure transmitted by the piston, means for locking the piston against movement and for releasing it at will, and means for causing the compression of the spring after the latter has been released.

2. A liquid receptacle and ejecting device 90 comprising a casing having a nozzle, said casing being arranged to receive a liquid, a spring pressed piston within said casing, said piston having an opening, a valve for closing said opening, said valve being automatically opened at one end of the stroke of the piston, means for locking the piston against the tension of the spring and for releasing the piston to permit the spring 100 to move the piston, thereby causing the ejection of the liquid.

3. A liquid receptacle and ejecting device comprising a casing, a piston within the casing, a screw shaft, a sleeve secured to said piston and having a nut arranged to 110 engage said screw shaft, an exterior cylinder feathered to said sleeve and a handle for said screw shaft.

4. A liquid receptacle and ejecting device comprising a casing, a piston within the 115 casing, a screw shaft, a sleeve secured to said piston and having a nut arranged to engage said screw shaft, an exterior cylinder feathered to said sleeve, a handle for said screw shaft, and a spring disposed within 120 said casing and arranged to bear at one end upon the end of the casing and at the other end upon said piston.

5. A liquid receptacle and ejecting device comprising a casing, a piston within the casing, a screw shaft, a sleeve secured to said piston and having a nut arranged to 125 engage said screw shaft, an exterior cylinder feathered to said sleeve, a handle for said screw shaft, and a spring disposed within said 130

casing and arranged to bear at one end upon the end of the casing and at the other end upon said piston, a port or passage through said piston and a valve for normally closing said port.

6. A liquid receptacle and ejecting device comprising a casing, a piston within the casing, a screw shaft, a sleeve secured to said piston and having a nut arranged to engage said screw shaft, an exterior cylinder feathered to said sleeve, a handle for said screw shaft, a spring disposed within said casing and arranged to bear at one end upon the end of the casing and at the other end upon said piston, a port or passage through said piston and a valve for normally closing said port, said valve having a portion normally in engagement with the end of the screw shaft for keeping the valve open.

7. A liquid receptacle and ejecting device comprising a casing, a piston within the casing, a screw shaft, a sleeve secured to said piston and having a nut arranged to engage said screw shaft, an exterior cylinder feathered to said sleeve, a handle for said screw shaft, a spring disposed within said casing and arranged to bear at one end upon the end of the casing and at the other end upon said piston, a port or passage through said piston, a valve for normally closing said port, said valve having a portion normally in engagement with the end of the screw shaft for keeping the valve open, and

a spring for closing the valve when the latter has been moved out of engagement with the end of the screw shaft.

8. A liquid receptacle and ejecting device comprising a casing having a nozzle, said casing being arranged to receive a liquid, a piston within the casing, a spring for placing said piston normally under tension, a valve adapted to open under pressure transmitted by the piston, means for locking the piston against movement and for releasing it at will, means for causing the compression of the spring after the latter has been released, said means comprising a hand wheel, a screw shaft secured to said hand wheel, and means operated by said screw shaft for retracting the piston.

9. A liquid receptacle and ejecting device comprising a casing having a nozzle, said casing being arranged to receive a liquid, a piston within the casing, a spring for placing said piston normally under tension, means for locking the piston against movement and for releasing it at will, means for causing the compression of the spring after the latter has been released, said means comprising a hand wheel, a screw shaft secured to said hand wheel, means operated by said screw shaft for retracting the piston, and a valve carried by the piston for permitting the passage of fluid through the piston when the latter is being retracted.

MILLARD E. BRINSER.
